TIE RACK

Lawrence F. Cuthbert, Ogdensburg, N. Y., assignor
to The Newell Mfg. Co., Ogdensburg, N. Y., a
corporation of Maine

Application September 19, 1933, Serial No. 690,157

3 Claims. (Cl. 211—96)

This invention relates generally to racks or hangers and refers more particularly to those designed to support ties or other similar articles in spaced relation, whereby selection of the ties is greatly facilitated.

An object of the invention is to provide a tie hanger and supporting bracket which may be easily and quickly installed upon a wall or door with the hanger normally lying flush against the same in an out of the way position but capable of being swung in the bracket to a convenient position for the selection of one or more ties.

Another and important object is to form the hanger and bracket of materials that may be stamped and shaped into the desired design without the necessity of performing costly machining operations, thus effecting a substantial savings in manufacturing costs.

Various other objects and advantages will appear in the description of the invention and as disclosed in the drawing.

In order that the invention may be clear to those skilled in the art, I have shown in the drawing herewith, and forming a part of this disclosure, one physical embodiment of my invention, and that the best now known to me.

In said drawing:—

Figure 1 is a view of the tie rack or hanger secured to the inner face of a closet door;

Figure 2 is a perspective view of the hanger and bracket therefor;

Figure 3 is a side elevation partly in section of a modified form of hanger; and

Figure 4 is a side elevation partly in section of still another modification of the hanger.

Referring to the drawing by numbers, like numbers indicating like parts in the several views, 10 indicates a closet door upon which is supported a tie rack or hanger 11 forming the subject matter of the present invention. The tie rack comprises a hanger bar 12 pivotally and removably supported in a bracket 13, the latter having upper and lower attachment portions 14 and an intermediate projecting approximately U-shaped bearing portion 15 forming spaced upper and lower lugs 16 and 17. These lugs are formed with vertically aligned circular openings 18 and 19 and the attaching portions 14 are provided with openings 20 for receiving attaching screws 21. The bracket is preferably formed from a piece of stock which is capable of being stamped and shaped without any machining operations.

The hanger bar 12 is also formed of stock material, preferably square in cross section with the inner end thereof bent at right angles to the

rest of the bar to form a pintle member 22. The relative sizes of the pintle member and the circular openings of the bearing portion are such as to permit the member to be readily dropped through the openings and turned therein so that the hanger bar may be moved from a position against the face of the door to one convenient for the selection and removal of ties 23 or other objects supported upon the hanger bar. For the purpose of keeping the ties, neatly arranged in spaced relation whereby one or more may be easily and quickly selected and removed without disturbing the other ties on the rack, the hanger bar is provided with a plurality of spaced pins 24.

To facilitate the turning or swinging movement of the pintle in the bracket, a pin 25 is secured to the pintle in any suitable manner, such as by piercing the pintle so that the pin projects through the same upon opposite sides thereof. With this arrangement, when the pintle is 20 dropped through the openings 18 and 19, the pin 25 will rest upon the upper lug 16 of the bracket and will support the hanger bar above and in spaced relation with the bracket, thus preventing any binding action between the bar and bracket 25 when swinging the former from one position to another.

It will be apparent that a tie rack constructed in this manner may be easily and quickly installed upon a door, wall or article of furniture with the hanger bar normally lying substantially flush against the same in an out of the way position. The hanger may be readily moved to an accessible position where one or more ties may be selected and removed without disturbing the remainder of the ties on the rack. By reason of the fact that both the bracket and the hanger bar may be easily and quickly stamped and shaped into the desired form out of stock material, without costly machining operations, quantity production is greatly facilitated with resultant low cost of manufacture.

In Figure 3, there is shown a modified form of the device in which the pintle member 26 is provided with a pin 27 having upwardly curved 45 projecting portions 28 presenting lower convex surfaces to the upper lug of the bracket. This provides an easy frictionless bearing which not only facilitates the turning movement of the pintle in the bracket, but also centers the pintle 50 in the aperture.

Another form of the invention is disclosed in Figure 4 in which the pintle member 29 is distorted to provide oppositely projecting bearing portions 30. As shown, these portions also pre-

sent lower convex surfaces to the bracket and likewise provide a frictionless bearing. Furthermore, the pintle member is centered in the bracket as in construction shown in Figure 3.

5 It will be observed that the hanger bar with its pintle may be formed of square commercial stock, thus reducing the cost of preparation, and this stock may be readily bent to dispose the pintle at right angles to the bar. Furthermore, this non-circular cross sectional form of the pintle provides a four-point contact only with the circular apertures, materially reducing the friction between the parts, and when the contact surface sustaining pin or part is inclined, as shown in Figures 3 and 4, a frictionless pintle-centering bearing is provided.

10 Such changes as involve merely mechanical skill may, of course, be made and still be within the range of my invention.

15 20 I claim:—

1. In a hanger of the class described, a hanger bar, a bar supporting bracket having upper and lower lugs provided with vertically aligned circular openings, an integral square pintle member on said bar mounted in the circular openings of

the lugs permitting pivotal movement of the bar, and a pin piercing the square pintle member and resting upon the upper lug and supporting the hanger bar above and in spaced relation with the same.

2. In a hanger of the class described, a hanger bar, a pintle member on said bar, a bar supporting bracket having an apertured pintle receiving lug, said pintle member being provided with oppositely projecting bearing portions resting upon and presenting lower inclined surfaces to the lug to provide a bearing and center the pintle member in the bracket.

3. In a hanger of the class described, a hanger bar, a pintle member on said bar, a bar supporting bracket having an apertured pintle receiving lug, and a pin piercing the pintle member and resting upon the lug and supporting the hanger bar above and in spaced relation with the same, the projecting portions of the pin being bent upwardly and presenting lower inclined surfaces to the bracket to provide a bearing and center the pintle member in the bracket.

LAWRENCE F. CUTHBERT.
